CLAIM

The ornamental design for a beverage can carrier, as shown and described.

DESCRIPTION

FIG. 1 is a perspective view of a beverage can carrier showing our new design, the cans shown in broken lines for illustrative purposes only;

FIG. 2 is a front elevational view thereof, the opposite side being a mirror image;

FIG. 3 is a top plan view thereof;

FIG. 4 is a right side elevational view thereof, opposite side being a mirror image; and

FIG. 5 is a bottom plan view thereof.

FIG. 1

FIG. 2

FIG. 3

FIG. 5

FIG. 4
